Patented Sept. 6, 1921.

FREDERICK W. PECK. Inventor

By Raymond A. Parker
Attorney

UNITED STATES PATENT OFFICE.

FREDERICK W. PECK, OF ROYAL OAK, MICHIGAN.

APPARATUS FOR AIR-COOLING CYLINDERS.

1,389,780.

Specification of Letters Patent.

Patented Sept. 6, 1921.

Application filed March 8, 1920. Serial No. 364,187.

To all whom it may concern:

Be it known that I, FREDERICK W. PECK, a citizen of the United States, residing at Royal Oak, county of Oakland, State of Michigan, have invented a certain new and useful Improvement in Apparatus for Air-Cooling Cylinders, and declare the following to be a full, clear, and exact description of the same, such as will enable others skilled in the art to which it pertains to make and use the same, reference being had to the accompanying drawings, which form a part of this specification.

My invention relates to cylinder cooling for internal combustion engines and an object of my improvements is to provide an apparatus for air cooling a cylinder which shall direct a draft of air against the cylinder and tubes or radiating parts and distribute it over the surface thereof at a uniform temperature. As hitherto constructed the current of air passed over the cylinder has come in contact with a portion of said cylinder at first and become somewhat heated and then passed to another portion of the cylinder to cool the latter at the temperature that it has acquired by contact with the first-named portion of the cylinder.

In my improvement the current of air is distributed over the surface of the cylinders so that it comes in contact with the various portions thereof at practically a uniform temperature.

In the accompanying drawing:

Figure 1 is an elevation partly broken away of an apparatus embodying my invention and so much of an engine cylinder as is necessary to illustrate its connection therewith.

Fig. 2 is a detail section.

Fig. 3 is a section similar to Fig. 1, showing a modified construction.

Fig. 4 is a detailed section on the line IV—IV of Figs. 2 and 3.

Fig. 5 is a detailed perspective view showing my modified form, the parts being disassembled.

Fig. 6 is a sectional view of the assembled parts of the modification shown in Fig. 5.

Fig. 7 is a sectional plan-view illustrating an arrangement of a modified form of tube.

Fig. 8 is a detail perspective illustrating the construction of Fig. 7.

a is the cylinder; *a*² indicates tubular cy-

lindrical projections from the outer surface of the cylinder *a*. These projections may be cast integral with the cylinder, as shown in Fig. 2, or they may be tubular pieces cast in the wall of the cylinder, as indicated in Fig. 3.

b is a casing inclosing the cylinder *a* and the projections or fins *a*², with a considerable space between its wall and the outer wall of said cylinder and preferably some space between its inner wall and the outer walls of the tubular projections *a*².

*b*³ is a passage leading from the casing *b*. *c* is a fan in the passageway *b*³ adapted to draw air from the casing *b*.

*b*² are tubular projections extending inward from the inner wall of the casing *b*, their bores opening to the outer air through apertures in the wall of the casing *b*. The projections *b*² extend into and are co-axial with the projections *a*², there being some space between the inner end of the tubes or projections *b*², the inner end wall of the projections *a*² and between the walls of the projections.

The operation of the above-described device is as follows:

The fan *c* being operated, air is drawn from the casing *b* and a partial vacuum formed therein so that the atmospheric air rushes in in jets through the projections *b*², such jets impinging against the inner end walls of the casing *a*² and passing outward along the inner walls of such projections to remove the heat therefrom as indicated by the arrows in Fig. 2.

Of course the fan *c* may be reversed and air blown into the casing *b* to form a plenum instead of a vacuum therein so that the direction of the current of air would be reversed, having the same effect.

Of course any other form of projections producing the same effect may be employed. For instance, as shown in Figs. 5 and 6 the ordinary circular fin or cooling rib *a*²*x* may be employed and a tubular projection, the walls of which are annular or are parts of annuli spaced from each other, may be used, the air current then taking the direction indicated by arrows in Fig. 6.

The air admission tube may take the form shown in Figs. 7 and 8 quite broad horizontally and narrow vertically so as to enter between the cooling ribs as ordinarily con-

structed and affording vertical passages x , x , x Fig. 7 to facilitate the vertical passage of the cooling air.

What I claim is:

- 5 1. The combination of a cylinder, cylindrical cavities having walls connected with the walls of said cylinder, a casing inclosing said cylinder and apertures formed through the walls of said casing opposite said cavities and at a distance therefrom and means for projecting a jet of air through said apertures.
- 10

2. The combination of a cylinder, cylindrical cavities having walls connected with the walls of said cylinder, a casing inclosing 15 said cylinder, apertures formed through the walls of said casing opposite said cavities, and tubes extending from the wall of said casing, their bores forming a continuation of said apertures and opening into said cavities. 20

In testimony whereof, I sign this specification.

FREDERICK W. PECK.
